UNITED STATES PATENT OFFICE.

HARTWELL W. WEBB, OF CRESSKILL, NEW JERSEY.

THERMAL SWITCH.

1,330,753.

Specification of Letters Patent. Patented Feb. 10, 1920.

Application filed March 11, 1918. Serial No. 221,743.

To all whom it may concern:

Be it known that I, HARTWELL W. WEBB, a citizen of the United States, and a resident of Cresskill, in the county of Bergen and 5 State of New Jersey, have invented certain new and useful Improvements in Thermal Switches, of which the following is a specification.

The present invention relates to automatic electric switches of the thermodynamic type, and is more particularly designed for periodically opening and closing of electric circuits, for instance those of the electric lamps of a sign or other electrically 10 operated advertising devices.

In the devices of this type heretofore in use, electric heaters have been employed which necessitate for operation a considerable amount of heat. Inasmuch as the heat 20 activity, or the heat-per-second, produced by an electric current is proportional to the electric power or the watts, it is obvious that these switches could be inserted only in such circuits which are of high electric 25 power.

The main object of the present invention is to produce a thermo-dynamic switch which can be made use of in connection with low electric power circuits, such as for instance with pocket flash lights, or generally 30 in connection with a few dry batteries or secondary cells.

Another object of the invention is to produce a switch of the character described, 35 which is simple in construction, inexpensive to manufacture, and which is capable of withstanding rough usage without getting out of order.

A further object of the invention is to so 40 construct the switch that its frame members constitute at the same time the terminals thereof, thereby being capable of insertion into the circuit of pocket flash lights without necessitating the provision of special 45 clamps or terminal screws.

With these and other objects in view, which will more fully appear as the nature of the invention is better understood, the same consists in the combination, arrangement, and construction of parts hereinafter 50 described, pointed out in the appended claims and illustrated in the accompanying drawings, it being understood that many changes may be made in the size and proportion of the several parts and details of 55 construction within the scope of the ap-

pended claims without departing from the spirit or sacrificing any of the advantages of the invention.

One of the many possible embodiments of 60 the invention is illustrated in the accompanying drawings, in which:—

Figure 1 is a top plan view of a switch constructed in accordance with the present invention; Fig. 2 is a section taken on line 65 2—2 of Fig. 1; Fig. 3 is a section taken on line 3—3 of Fig. 1; Fig. 4 is a perspective view of a section of one of the conductors of the switch; Fig. 5 is a perspective view of another section of the conductor 70 cooperating with that shown in Fig. 4 of the drawings; and Fig. 6 is a diagram illustrating the manner of connecting the improved switch to a lamp and its circuit.

In the drawings, the numeral 10 indicates 75 the base plate of the switch, said plate being made, preferably, of an electric conducting material, such as for instance metal, and being preferably of disk shape, so as to be insertible into pocket flash lights 80 of the cylindrical type. From this plate rises a lug 11, shown in the present case as being made integral with the base plate, although this feature is not essential. The lug is bent substantially at right angles to 85 the base plate and is provided with a screw threaded hole 12. With the threads of this hole mesh those of a screw bolt 13, that extends in radial direction in a plane parallel to that of the base plate. The free end portion of the bolt is provided with a longitudinal bore 14, said bored portion being split, as clearly shown at 15. Into the bore of the bolt extends the reduced portion 16 of a 90 companion bolt 17. The diameter of the screw threaded body portion 18 of the companion bolt corresponds to that of the screw threaded portion of the bolt 13. Both bolts are made of electric conducting material, preferably metal, the reduced portion 16 of 100 the companion bolt being slidable in the bore of the bolt 13, but maintaining always electric contact with the bolt 13. The latter bolt is split to permit of easy sliding of the said companion bolt. Over the two bolts is 105 drawn a sleeve 19 of electric insulating material, preferably hard rubber, one end of said sleeve abutting against the lug 11. This sleeve is provided with interior screw threads near both of its ends; those on one 110 end meshing with the threads of the bolt 13 and those on the other end with the threads

on the bolt 17. The companion bolt 17 is provided beyond the sleeve 19 with a head 20, on which is centrally formed a contact point 21. Upon the sleeve is wound a heating coil 22, which is of a very small size and consequently of high resistance.

From the base plate 10 rises a frame member 23 of electric conducting material, such as metal, said frame member being insulated from the base plate by insulating material 24. Screws 25 serve to secure the frame member to the base plate, said screws being insulated from the said frame member by insulating disks 26. The frame member 23 is provided with a downwardly extending lug 27, having a screw threaded hole 28 in alignment with the hole 12 in the lug 11. With the threads of the hole 28 mesh those of a set screw 29, having a contact point 30 in proximity of and in registering position with the contact point 21 on the companion bolt 17.

One end of the heating coil 22 is electrically connected with the lug 11, and its other end with the frame member 23. From this it appears that the said coil is connected in a shunt around the switch contact points.

As illustrated in the diagram in Fig. 6, one terminal of an electric battery 31 is connected by a battery conductor 32 with one terminal of an incandescent lamp 33, the other terminal of which is connected by an electric conductor 34 with the frame member 23. The base plate 10, on the other hand, is connected by an electric conductor 35 with the other terminal of the battery.

With the connections described, current will normally flow from the battery 31 through the wire 32 to the lamp 33, thence through wire 34 to frame member 23, through the heating coil 22 to the base plate 10, and through the wire 35 back to the battery. The heating coil is thus in series with the lamp, and its relative resistance is so high that the amount of current passing through the circuit will be insufficient to light the lamp. The current flowing through the circuit, however, will be sufficient to heat the coil 22 and thus the insulating sleeve 19, so that the latter will expand mainly in the direction of its longitudinal axis until the contact point 21 on the companion bolt 17 is brought into engagement with the contact point 30 on the set screw 29. Upon such engagement, a low resistance shunt is formed around the heating coil, and the current will flow from the battery 31 by conductor 32 to the lamp 33, thence by conductor 34 to frame member 23, through set screw 29 to bolts 17 and 18, and through base plate 10 and conductor 35 back to the battery. The low resistance circuit thus formed permits a light current to pass and the lamp will flash out brightly. Inasmuch as the resistance

of the coil is very high compared to that of the circuit formed when the contacts are in engagement, only a small or practically no current will flow through the heating coil so that the latter and the insulating sleeve will cool, with the result that the said sleeve contracts and breaks the contact between the points 21 and 30. In this manner the heating coil is again interposed in the circuit, with the result that the lamp is dimmed or becomes entirely dark. The cycle of operations now described is then repeated.

The device as herein described is particularly useful in connection with pocket flash lights of the cylindrical type, in which the battery is held in place by a spring bearing against the same and against the screw cap at the bottom of the casing. The device may be conveniently inserted into such flash lights, its frame member 23 and base plate 10 being interposed in the circuit without the aid of any additional wires, clamps, etc.

Inasmuch as only linear expansion of the insulating sleeve 19 is necessary to close the switch, the device can be conveniently operated by low electric power circuits, in contradistinction to the devices heretofore in use in which the expansion device had to be bent or bowed to make contact, or in other words necessitated considerable power and thus heat energy for operation.

It is obvious that while herein both the base plate 10 and the frame member 23 have been described as being made of electric conducting material, these parts may be made of other material, and the conductors 34 and 35 connected with the set screw 29 and bolt 13 without departing from the invention, which lies mainly in the provision of an expansion device making and breaking the contact by motion in the direction of its longitudinal axis.

The sleeve 19 has been made of insulating material for two reasons, to wit: first, it permits uninsulated wire to be used in constructing the heating coil, second, its coefficient of expansion is considerably more favorable than those of the metallic expansion members heretofore generally employed.

What I claim is:

1. In thermo-dynamic switch, the combination with a base, of a frame mounted thereon, a stationary contact point on said frame, a bolt on said base extending toward said stationary contact point and provided with a bore, the bored portion of said bolt being split, a second bolt having its inner end slidably arranged in the bore of said first bolt and carrying upon its outer end a contact point disposed in proximity of said stationary contact point, a sleeve drawn over said two bolts and fastened thereto, one end of said sleeve abutting against said base, and a heating coil wound upon said sleeve and

connected in a shunt around said contact points.

2. In a thermo-dynamic switch, the combination with a base of electric conducting material, of a frame of electric conducting material mounted thereon and insulated therefrom, a stationary contact point on said frame, a bolt on said base extending toward said stationary contact point and provided 10 with a bore, the bored portion of said bolt being split, a second bolt having its inner end slidably arranged in the bore of said first bolt, and carrying upon its outer end a contact point disposed in proximity of said 15 stationary contact point, both bolts being made of electric conducting material, a sleeve of electric insulating material drawn over said two bolts and fastened thereto, one end of said sleeve abutting against said base, 20 and a heating coil wound upon said sleeve and connected in shunt around said contact points to said base and frame.

3. In a thermo-dynamic switch, the combination with a base, of a frame mounted 25 thereon, a stationary contact point on said frame, an expansion member upon said base having one of its ends abutting against said base and its other end free in proximity of

said stationary contact point, a bolt extending through said expansion member made of 30 two continuously contacting sections, one of which is fixed to and in electric contact with said base and the other one fixed to the free end of said expansion member, thereby forming a movable contact point, and a 35 heating coil wound upon said expansion member and connected to said base and said stationary contact point.

4. A thermo-dynamic switch, including a stationary contact point, an expansion member having a fixed end and a free end in proximity of said contact point, a bolt extending through said expansion member made of two continuously contacting sections, one of which is fixed to the fixed end 40 of said expansion member and the other one secured to the free end of said expansion member, thereby forming a movable contact point, and a heating coil wound upon said expansion member and connected to the 45 fixed section of said bolt and said stationary contact point.

Signed at New York, in the county of New York and State of New York, this 26th day of Feb., A. D. 1918.

HARTWELL W. WEBB.
